UNITED STATES PATENT OFFICE

95,319

DESIGN FOR A BEVERAGE GLASS CLEANSER

William H. Eaton and Ivan L. Follett,
Santa Barbara, Calif.

Application January 3, 1935, Serial No. 54,713

Term of patent 7 years

To all whom it may concern:

Be it known that we, William H. Eaton and Ivan L. Follett, citizens of the United States, residing at Santa Barbara, in the county of Santa Barbara and State of California, have invented a new, original, and ornamental Design for a Beverage Glass Cleanser, of which the following is a specification, reference being had to the accompanying drawing, forming part thereof.

Fig. 1 is a front elevation, and

Fig. 2 is a top plan view of the beverage glass cleanser showing our new design.

The bristles shown at the top of the brushes in Fig. 1 are not shown in Fig. 2 in any manner to distinguish them from subjacent bristles.

We claim:

The ornamental design for a beverage glass cleanser as shown and described.
